UNITED STATES PATENT OFFICE

RUSSELL L. GOGIN, OF WILTON, MAINE, ASSIGNOR TO G. H. BASS & CO., OF WILTON, MAINE, A CORPORATION OF MAINE

MOCCASIN CONSTRUCTION

Application filed September 24, 1930. Serial No. 484,063.

In the manufacture of footwear of moccasin type which are characterized by a toe piece and vamp seamed together at the upper portion of the foot, much difficulty has been experienced in getting strength and tightness in the seam particularly in that region at the base of the instep where the moccasin is creased under the foot flexion of the wearer.

As moccasins are usually flexible sole foot-
10 wear the wearer is encouraged to flex the foot freely so that the joints between the metatarsals and the phalanges are brought more into action than with the stiff sole types of shoe. This freedom of action of the foot is highly
15 desirable and strongly recommends the moccasin as a foot covering. The resultant creasing, however, tends to open up or disrupt the seam between the upper and vamp in this very important region. This particular portion of the moccasin not only usually receives its maximum strain, but also is particularly exposed to moisture and due to the nature of their use moccasins are usually made as near waterproof as possible.

20 Various efforts have been made to overcome this difficulty by multiplied or complicated seams, but these have been expensive and in many instances cumbersome or unsightly. The object of my present invention is to provide a novel structure in the moccasin which is simple and inexpensive, but which has proven to be of great efficiency in meeting those difficulties long familiar to the manufacturer and user.

25 Briefly stated, I effect this by introducing into the structure a bearing inclusive of the zone on each side of the foot and extending across the ends of the creased zone which forms in the toe piece after being worn. For the purposes of illustration I have selected a form of moccasin of generally standard type embodying my invention. This is illustrated in the drawings as follows:

30 Fig. 1 is a somewhat diagrammatic view of a moccasin in the position of flexion.

Fig. 2 is an outline or pattern of toe piece and tongue having my lateral bearing flanges.

35 Fig. 3 is a transverse view through the re-
gion 3—3, Fig. 1, and

Fig. 4 is a section through the toe piece, on the line 4—4, Fig. 2.

In the form shown in the drawings I provide the usual vamp 1 and a toe piece 2 having a tongue portion 3. Just below the tongue portion and laterally of that portion of the toe piece which would come over the joints between the metatarsals and the phalanges I provide lateral bearing pieces or side extension areas 4. These are in assembly brought under the vamp and secured to its inner face. The bearing portions 4 are preferably skived and are cementitiously united to the inner or flesh side of the vamp, thus giving a deep bearing along the side of the foot in the zone 65 of its major flexion.

As appears in the somewhat diagrammatic view, Fig. 1, and as indicated therein by the broken lines, this makes a stay across the pucker zone so that the seam 5 is reinforced 76 and protected. It is also to be noted that this flap member 4 of the toe piece receives the puckerings of the vamp which are drawn up in making the seam 5.

Footwear of this type may be variously 75 designed according to any of the known types or patterns and the parts may be variously seamed, waterproofed and otherwise finished as may be desired. While the cementing of the flap portion 4 is of great ad- 80 vantage, this flap portion could, of course, be stitched or both stitching and cement could be used. In some instances as where the lateral areas are continued around the toe the seam may be cemented and the sew- 85 ing omitted. It is found in practice that by making the flap portion 4 of considerable area so as to get a broad bearing and cementitiously uniting, a very strong and water- 90 proof zone is formed in the moccasin. This bearing not only withstands the strains trans- 95 versely of the footing, but takes up those longitudinal flexations in material which causes the wrinkling and which have heretofore caused the opening or breaking of the seam at this point. The construction is inexpensive and makes unnecessary many elaborate and difficult expedients heretofore resorted to in the attempt to overcome this difficulty. 100

What I therefore claim and desire to secure by Letters Patent is:

In footwear of the moccasin type, a toe piece structure to substantially overlie the top 5 of the foot, a vamp to substantially embrace the sides of the foot, a seam uniting the toe piece structure with the vamp, and flaps formed as downward extensions of the toe piece structure and fastened to the sides of 10 the vamp below the seam, said flaps being of a width to extend from the seam downwardly a sufficient distance to substantially overlie the sides of the ball portion of the foot, thus to effectively reinforce and stiffen the vamp 15 in the pucker region whereby sharp pockers are eliminated and whereby the stress is distributed substantially uniformly over this area to prevent breakage of the seam.

In testimony whereof I affix my signature.
